Letters Patent No. 1003, dated May 11, 1858.

The schedule referred to in these Letters Patent and making part of the same.

To all whom it may concern:-

Be it known that I, S. W. Gibbs in the City of Albany in the County of Albany, and State of New York, have invented or produced a new and original ornamental design for the plates of an Elevated Oven Cooking Stove, and I do hereby declare that the following is a full and exact description of the same reference being had to the accompanying drawings, and to the letters of reference marked thereon.

Fig. 3. represents the front of oven of said Elevated Oven cook stove, I claim as original the configuration of the panel A of the said oven front of the said stove, also the moulding B, which forms the said panel, also the ornaments running up the corners of the said front of oven, marked C, the whole forming in combination, and peculiar disposition thereof, the ornamental front of oven, of the herein above named Elevated Oven Cooking Stove. Fig. 2. represents the oven door of said stove, the moulding forming the outer edge of said door is of the same figure as that forming the panel on the front of the oven. The ornament D, being placed in the center of the panel formed by said mouldings, the whole forming in combination and peculiar disposition thereof, an ornamental oven door for said Elevated Oven Stove. Fig. 1. represents a lower door, or door of lower front of said stove.

The moulding forming the outer edge of said door, being the same figure as that of the oven door and oven panel, The ornament E is placed in the center of the panel formed by the said moulding, the whole forming in combination, and peculiar disposition thereof, an ornamental lower front door of said Elevated Oven Stove.

What I claim as my production and desire to secure by letters patent, is the ornamental design, and configuration of the
